UNITED STATES PATENT OFFICE

FREDERICK A. BALLOU, OF NAYATT, RHODE ISLAND, ASSIGNOR TO B. A. BALLOU & CO., INC., OF PROVIDENCE, RHODE ISLAND, A CORPORATION OF RHODE ISLAND

SHOE STRAP

Application filed September 30, 1927. Serial No. 223,195.

This invention relates to an improved construction of shoe strap; and has for its object to provide an ankle strap of an ornamental character and of a length to extend over the instep of the wearer and be connected to the opposite sides of the marginal edges of the shoe upper.

A further object of the invention is the provision of means in the strap intermediate its ends by which the strap may be separated without disconnecting the ends of the strap from the shoe.

With these and other objects in view, the invention consists of certain novel features of construction, as will be more fully described, and particularly pointed out in the appended claims.

In the accompanying drawings:

Figure 1 is a view of my improved shoe strap with its ends connected to the shoe and a clasp in the strap intermediate its ends.

Figure 2 is the same as Figure 1 but showing the strap with the clasp members disconnected at a point intermediate the ends of the strap.

Figure 3 is an enlarged view of a strap detached showing the same as constructed in a continuous unit with its ends arranged to be riveted, sewed or otherwise permanently connected to the opposite sides of the shoe.

Figure 4 shows a strap detached and as provided with a center clasp by which it may be disconnected at a point intermediate its ends without disconnecting from the shoe.

Figure 5 shows a strap unit having an enlarged central ornamental link to one or both sides of which the other links of the strap are detachably connected.

Figure 6 is an edge view of the construction shown in Figure 5.

Figure 7 shows one form of center clasp by which the abutting links of the strap chain may be disconnected.

Figure 8 shows one form of chain links which are spring pressed to form an extendible chain.

It is found in practical use of shoe straps of this character of advantage, in some instances, to secure the ends of the strap permanently to the sides of the shoe upper and

to provide simple means by which the strap may be disconnected at a point intermediate its ends, thus obviating the necessity of detaching its ends from the shoe, as in some instances the end clasp after having been detached may not be connected exactly in the same place as before and, therefore, roughen up or mar the surface of the shoe and in such cases it is found of advantage to be able to provide suitable means whereby the strap may be separated at a point intermediate its ends to obviate such disconnecting from the shoe. In some instances, I use a clasp by which the abutting ends may be detachably connected. In other instances I may use a hook or other connecting element for attaching the abutting ends of the chain links together, while in still other instances I may employ a chain having sufficient elasticity to yield and permit the foot to pass into the shoe without the necessity of disconnecting the strap either at its ends from the shoe or at points intermediate these attached ends; and the following is a detailed description of the present embodiment of my invention and showing one means by which these advantageous results may be accomplished:—

With reference to the drawings, 10 designates the body portion of the strap which is preferably formed of an extendible chain. 80 This chain may be ornamented on its outer surface or may be covered with an extendible ornamental envelope or casing such for instance as being incased in a so-called live leather tube or the like. The strap body itself, however, is preferably formed of a plurality of link units 11, see Figure 8, each unit comprising an outer box-shaped member having an inner channel shaped member slideable therein and normally pressed to contracted position by a spring 13.

Any suitable number of these links may be connected together to extend over the instep of the wearer and to the opposite ends of these links may be connected a clasp 14, as shown in Figures 5 and 6 or to these ends may be connected a tab or eye member 15 adapted to be sewed or riveted or otherwise permanently attached in position to the opposite marginal edges of the shoe upper. In some instances, 100

the links of the strap may be of sufficient elasticity to permit the foot to pass into the shoe without disconnecting the strap ends from the shoe upper while in other instances a suitable clasp may be employed such for instance as that illustrated in Figure 7 in which a clasp hook 16 is adapted to be inserted and snapped into the opening 17 of the next adjacent link and having a presser finger 18 adapted when depressed to disconnect the edge 19 of the clasp hook from the inturned flange 20 of the next link. In other instances an enlarged ornamental link 21 may be employed, the same having a bail or loop 22 at one or both ends into which a hook 23 formed on the end link 24 may be snapped whereby the chain strap may be readily disconnected at a point intermediate its ends to facilitate the entering of the foot of the wearer into the shoe.

20 My improved form of shoe strap is very simple and practical in construction and may be formed very ornamental and by its use any possible disfiguration of the shoe by connecting or disconnecting the clasp thereto, is prevented.

25 The foregoing description is directed solely towards the construction illustrated, but I desire it to be understood that I reserve the privilege of resorting to all the mechanical changes to which the device is susceptible, the invention being defined and limited only by the terms of the appended claims.

I claim:

30 1. A shoe strap formed in two separable parts to extend over the instep of the wearer and having opposite end portions adapted to be attached to the opposite edges of the shoe upper, said two parts being flexible and of substantially uniform thickness and having 35 abutting end portions, and means for detachably connecting said abutting end portions together.

40 2. A shoe strap of a length to extend over the instep of the wearer to substantially the opposite side margins of the shoe formed in two separable parts each consisting of extendible metal units flexibly connected together, means associated with the opposite ends of the strap for adapting it to be connected to the margins of the shoe, said parts having abutting end portions intermediate the ends of the strap, and separable fastening means carried by said end portions for detachably connecting said abutting end portions together.

45 3. A shoe strap of a length to extend over the instep of the wearer to substantially the opposite side margins of the shoe formed in two separable parts each consisting of extendible metal units flexibly connected together, means associated with the opposite ends of the strap for adapting it to be connected to the margins of the shoe, said parts having abutting end portions intermediate the ends of the strap, and separable fastening

means consisting of formations on one of said end portions and a member on the other of said end portions for detachably engaging said formations for detachably connecting said abutting ends together.

50 4. A shoe strap of a length to extend over the instep of the wearer to substantially the opposite side margins of the shoe formed in two separable parts each consisting of extendible metal units flexibly connected together, means associated with the opposite ends of the strap for adapting it to be connected to the margins of the shoe, said parts having abutting end portions intermediate the ends of the strap and separable fastening means consisting of formations on one of said end portions, and a resilient member on the other of said end portions for engaging said formations to secure the abutting end portions together, said member permitting detachment upon being flexed for disengaging said end portions without disengaging the ends of the strap from the shoe.

55 5. A shoe strap formed in two separable parts to extend over the instep of the wearer and having opposite end portions adapted to be attached to the opposite edges of the shoe upper, said two parts comprising a plurality of links hingedly connected together and having abutting end portions, and means for detachably connecting said abutting end portions together.

60 In testimony whereof I affix my signature.

FREDERICK A. BALLOU.
